UNITED STATES PATENT OFFICE.

SAMUEL D. MOTT, OF PASSAIC, NEW JERSEY.

FLYING-MACHINE.

1,057,444.

Specification of Letters Patent.

Patented Apr. 1, 1913.

Application filed February 17, 1909. Serial No. 478,418.

To all whom it may concern:

Be it known that I, SAMUEL D. MOTT, a citizen of the United States, residing at Passaic, in the county of Passaic and State of New Jersey, have invented certain new and useful Improvements in Flying-Machines, of which the following is a specification, reference being had therein to the accompanying drawings, which form a part thereof.

My invention relates to flying machines, and more particularly to those of the helicopter type.

The main object of the invention is to provide a flying machine of the helicopter type wherein the direction of flight or horizontal traverse is controlled by the shifting of the center of gravity and the resultant change in the plane of rotation of the propeller, with means whereby the center of gravity may be changed by a swiveling movement of the car and its normally overbalanced load about the axis of the propeller, and thus avoiding the necessity for changing the load relative to the car itself.

A further object is to provide in a flying machine of this character, a seat for the operator, or occupants which may be shifted toward and from the axis of the propeller, to change the center of gravity in a manner to vary the angle of inclination of the propeller and control the horizontal component of movement of the entire machine.

A further object is to provide in a machine of this type a steering apparatus which will utilize the air resistance due to the horizontal component of movement to effect the swiveling of the car and its load to change the center of gravity about the axis of the propeller. And a still further object is to provide a steering apparatus which may be controlled from a point fixed relative to the car which will be simple in design and reliable in use, and which will not add materially to the weight of the apparatus or use any of the power of the motor to operate same.

The invention consists primarily in the combination in a flying machine of the helicopter type, of a propeller having a vertical lift, a motor rotating said propeller, a normally overbalanced car having a swivel relation to said propeller, whereby a horizontal component of movement results from said propeller, and a steering apparatus comprising a rudder projecting radially of

said propeller and hinged to the overbalanced car, and means whereby said rudder may be turned to swivel said car about the axis of said propeller; and in such other novel features of construction and combination of parts as are hereinafter set forth and described and more particularly pointed out in the claims hereto appended.

Referring to the drawings:—Figure 1 is a side elevation of a machine embodying my invention, the showing being of the car on a level keel; and Fig. 2 is a plan view thereof.

Like letters refer to like parts in both of said views.

In this type of flying machine which is made the subject matter of my pending application, Serial No. 125,376, filed Sept. 30, 1902, the car is sustained by a propeller having a vertical thrust and is given a horizontal component of movement by tilting the entire machine to the horizontal by shifting the center of gravity radially of the axis of rotation of the propeller. The car is pendant from and has a swivel relation to the propeller, which latter consists of oppositely rotated concentric vanes to cause one to absorb the reaction of the other and preserve the car in a position stationary relative to the propeller.

In my present invention, I aim to provide simple means for shifting a normally overbalanced car circumferentially of the main power propeller so as to change the center of gravity relative to said propeller and thus control the direction of flight of the machine.

In the accompanying drawings, *a*—*b* indicates two sets of rotary vanes in parallel planes, mounted on concentric shafts *a'*—*b'*, driven from the engine *d* by means of bevel gears *c* on the engine crank shafts, which gears are in mesh with oppositely disposed bevel gears *a''*—*b''* carried by the shafts *a'*—*b'* respectively. This construction results in the rotation of the sets of vanes *a*—*b* in opposite directions so that the reaction of one set is absorbed by the other.

The car *e* is pendant from the shafts *a'*—*b'*, the manner of suspension being such as to permit the car to swivel relative to the propeller, a ball bearing suspension *f* being preferable.

Below the engine *d* and suitably braced relative to the tank *g* is a frame *h* having frame having rails *g'*—*g''*. At opposite points

of this frame are the seat *i* and rudder *j*. The seat *i* is hinged to the rail *g'* and adjustably sustained on a screw threaded rod *k* pivotally connected to the rail *g²*, by an adjustment nut *k'*, so that the seat may be positioned relative to the axis of rotation of the propeller *a b* so as to regulate the normal pitch of said propeller to the horizontal.

The rudder *j* is hinged to both rails *g'* *g²* in any desired or approved manner, and may be made of metal having low specific gravity, wood, or any other suitable material. Preferably the free edge of said rudder is so shaped as to extend at substantially right angles to the course being described by the machine in flight. Extending laterally from opposite sides of the propeller, are rods *l l'* to which are attached the rudder lines or chains. Suitable stays *m* extend from the rudder to said rods to give rigidity thereto coupled with lightness of structure. The rudder *j* is positioned in substantial alignment with the center of resistance of the machine.

Projected forwardly of the frame *g* are side rails *n* carrying a foot rod *n'*. Extending from a ring *d'* about the engine frame to the foot rod *n'* are stays *n²*. Secured to these stays in front of the seat *i* are a hand rail *o* and a short rod *o'* which carry respectively, a bearing for the steering wheel *p*. This steering wheel is preferably centered on the longitudinal center line of the machine to secure the desired equipoise. While it may be positioned in any desired manner by using counterweights, the arrangement described is more desirable as excess weight is to be avoided in any "heavier than air" machine. Said wheel has a drum *p'* around which pass the steering lines or chains *q* passing through the guides *r* on each side of the top rail *g'* and are attached to the outer ends of the rods *l l'*, respectively.

The side rails *n* forwardly of the point of support of the seat *i* carry traction rollers *s* adapted to receive the first impact of the machine in landing and prevent the toppling thereof. The frame *g* has lateral extensions *g³* carrying anchor spikes *g⁴* for checking a forward movement of the machine when on a level keel on the ground.

In operation, the occupants or operators sit in the seat *i*, and so position the load as to normally overbalance the machine when the vertical thrust of the power propeller *a b* raises the car *e* from the ground. This overbalancing tilts the propeller in a direction in which the occupants or operators face, thus resulting in a horizontal component of movement to the entire machine giving a horizontal flight with an upward component of movement until the thrust of the propeller *a b* is equalized with the force of gravity acting on the

machine. When this condition exists, the propeller *a b* will sustain the machine in the air, and give a horizontal traverse proportionate to the power developed and the angle of inclination of the propeller. As the machine leaves the ground, its direction of horizontal traverse will be in a direction predetermined by the location of the overbalancing load. The speed of traverse, aside from that variance in the power developed by the motor *d*, will be determined by the angle of inclination of the propeller *a b*, which pitch will be determined by the distance of the overbalancing load from the axis of rotation of the propeller. Hence to regulate the pitch, the seat *i* may be adjusted radially of the propeller by means of the adjustment nut *k'*, the pivotal connection of the seat with the top rail *g'* and of the rod *k* with the rail *g²*, permitting the seat to swing toward said axis of rotation. The car, however, will normally be overbalanced no provision being made to poise the machine in the air.

If it be desired to describe a curve to the left, the left steering line or chain *q* is shortened, and the right one lengthened, by turning the hand wheel *p*. This results in the turning of the rudder *j* on its hinges so as to present a resistance surface to the air to the left of the longitudinal center of the machine, and thus produce an external force acting tangentially of a radius diametrically opposite to that on which the seats *i* project, thus swiveling the car laterally and shifting the overbalancing load circumferentially of the propeller *a b*, thus changing the plane of rotation of the said propeller *a b* with a resultant change in the direction of traverse of the entire machine. It will be observed, that this change is accomplished by swiveling the car alone. The stays *m* extending to the outer end of the rods *l l'* will sustain a portion of the external force developed by the rudder *j* thus permitting lightness in the construction of the rudder.

If it be desired to turn to the right, the rudder *j* is thrown to the right, the angle of said propeller coupled with the speed of flight controlling the radius of the curve described. The propeller being positioned with relation to the center of resistance, it will have no tendency to vary the speed of flight by changing the angle of inclination of the propeller *a b*.

The framework of the machine is preferably made of steel tubing, or other structural material uniting strength and lightness, and tension wires, thus not only reducing the weight of the machine but limiting the load to be moved by the rudder *j*.

In alighting, the rollers *s* would first encounter the ground, permitting the machine to travel thereover for a short distance until

gravity brought the machine to a level keel, whereupon the anchor spikes g^4 would check such movement.

The steering mechanism described accomplishes the swiveling of the car by a simple expedient for developing the necessary external tangential force. I am aware that this expedient *per se* is not new to the useful arts, but I believe it to be new to accomplish the physical movement of the car of a helicopter by swiveling it relative to the propeller or propellers, by the combination of parts herein shown and described.

Having described the invention, what I claim as new and desire to have protected by Letters Patent, is—

1. In a flying machine of the helicopter type, the combination of a propeller having a vertical lift, a motor rotating said propeller, a normally overbalanced car having a swivel relation to and movable about an axis coincident with the axis of said propeller, whereby a horizontal component of movement results from the tilting of said propeller, and a steering apparatus comprising a rudder projected radially of said propeller and hinged to the overbalanced car, and means whereby said rudder may be turned to cause the resistance thereof to swivel the car about the axis of said propeller.

2. In a flying machine of the helicopter type, the combination of a propeller having a vertical lift, a motor rotating said propeller, a car having a swivel relation to and movable about an axis coincident with the axis of said propeller, load carrying means on said car projected radially from the axis of rotation of said propeller whereby said car is normally overbalanced and a horizontal component of movement results from the tilting of said propeller, and a steering apparatus comprising a rudder projecting from a diametrically opposite radius of said propeller, and hinged to said car, and means whereby said rudder may be turned to cause the resistance thereof to swivel the car about the axis of said propeller.

3. In a flying machine of the helicopter type, the combination of a propeller having a vertical lift, a motor rotating said propeller, a car having a swiveling relation to and movable about an axis coincident with the axis of said propeller, load carrying means on said car projected radially from the axis of rotation of said propeller, whereby said car is normally overbalanced, and a horizontal component of movement results from the tilting of said propeller, and a steering apparatus comprising a rudder presenting parallel vane surfaces projecting

from said car diametrically opposite the radius of said load carrying means, a hinged connection between said rudder and said car, laterally projecting rods on the opposite sides of said rudder, a steering wheel having a drum thereon, ropes or chains extending from said rods about said drum, whereby said rudder may be turned to cause a resistance to swivel the car relative to said propeller.

4. In a flying machine of the helicopter type, the combination of a propeller having a vertical lift, a motor rotating said propeller, a car having a swiveling relation to and movable about an axis coincident with the axis of said propeller, load carrying means on said car projected radially from the axis of rotation of said propeller, whereby said car is normally overbalanced, and a horizontal component of movement results from the tilting of said propeller, and a steering apparatus comprising a rudder presenting parallel vane surfaces projecting from said car diametrically opposite the radius of said load carrying means, a hinged connection between said rudder and said car, laterally projecting rods on opposite sides of said rudder, stays extending from the ends of said rods to divergent points on the surface of said rudder, a steering wheel having a drum thereon, ropes or chains extending from said rods about said drum, whereby said rudder may be turned to cause a resistance to swivel the car about the axis of said propeller.

5. In a flying machine of the helicopter type, the combination of a propeller having a vertical lift, a motor rotating said propeller, a car having a swiveling relation to said propeller, including a frame having circular rails, a seat hinged to the upper of said rails, a screw threaded rod hinged to the lower of said rails, a keeper on said seat encircling said rod and an adjustment nut whereby said seat may be adjusted radially of said propeller, and a steering apparatus comprising a rudder hinged adjacent to the bottom and top thereof to said rails and projecting radially of the axis of rotation of said propeller, diametrically opposite said seat, and means whereby said rudder may be turned to cause the resistance thereof to swivel the car about the axis of said propeller.

In witness whereof, I have hereunto affixed my signature, this 25th day of January, 1909, in the presence of two witnesses.

SAMUEL D. MOTT.
